DESIGN FOR A GASOLINE DISPENSING PUMP

George T. Hudspeth, Dallas, Tex.

Application October 21, 1935, Serial No. 59,176

Term of patent 14 years

To all whom it may concern:

Be it known that I, George T. Hudspeth, a citizen of the United States, residing at Dallas, in the county of Dallas and State of Texas, have invented a new, original, and ornamental Design for Gasoline Dispensing Pumps, of which the following is a specification, reference being had to the accompanying drawing, forming a part thereof.

Figure 1 is a side elevation of a gasoline pump, showing my new design; and

Figure 2 is a front elevation thereof.

I claim:

The ornamental design for a gasoline dispensing pump as shown.

GEORGE T. HUDSPETH.
